UNITED STATES PATENT OFFICE.

RAYMOND L. WEGEL, OF NEW YORK, N. Y., ASSIGNOR TO WESTERN ELECTRIC COMPANY, INCORPORATED, OF NEW YORK, N. Y., A CORPORATION OF NEW YORK.

LOUD SPEAKER.

Original application filed April 30, 1923, Serial No. 635,407. Divided and this application filed December 1, 1925. Serial No. 72,449.

This invention relates to acoustic apparatus, the object being to provide an acoustic device capable of faithfully and efficiently reproducing sound vibrations within the 5 audible range.

This is a division of my application, Serial No. 635,407, filed April 30, 1923.

In accordance with the general features of the invention, there is provided an improved form of diaphragm and mounting whereby the system may have symmetrical modes of vibration, sensibly such that if the lowest mode gives sharp resonance, it will be well below the voice range, or if it gives 15 broad resonance it may be in the lower part of the voice range, and means for matching the impedance of the driving element to that of the diaphragm whereby the vibrations may be efficiently and faithfully transmitted.

20 It is a well known fact that tones low in the musical scale are heard less distinctly than those high in the scale. This may be due to the ear being less sensitive to the lower frequency tones giving the impression that

25 less energy is involved in producing them. However, more pleasing effects may be obtained if the lower notes can be produced more distinctly. The horns usually heretofore employed in connection with talking

30 machine and loud speaking receivers are inefficient transformers of acoustic vibrations at the frequencies for which the ear is less sensitive. In many cases, therefore, the low notes appear to be entirely eliminated. It

35 has been found that large diaphragms, when properly designed, reproduce the lower notes very efficiently. Other things being equal, the larger the diaphragm the lower its fundamental mode of vibration and the same

40 diaphragm, when free, has a lower natural period than when rigidly secured at its periphery. In accordance with the invention a diaphragm preferably conical in form to permit the use of light materials and obtain the proper amount of stiffness is provided with an elastic mounting such that

45 for low frequencies substantially the whole of the diaphragm may vibrate. This arrangement possesses certain of the advantages

50 of a free diaphragm and has a further advantage of added stiffness whereby the circular symmetry of the diaphragm is maintained while vibrating. Such a device will faithfully and uniformly transmit vibra-

tions throughout the voice range and will 55 amplify the low frequency vibrations in the musical scale to the extent that they will have the proper relative sound intensity relative to the higher frequency vibrations.

In the particular embodiment of the invention to be described and illustrated in the present application, the acoustic device comprises as a front member a relatively large sheet of thin, light material formed to possess inherent stiffness, such as by being 60 made in conical form, and an elastic supporting member secured to the rear or hollow side of said sheet and extending inwardly in all directions so as to form with the front member a partially enclosed chamber. Means are provided for vibrating the front member in accordance with the sounds to be produced. The rear member is suitably mounted on a support, in the present instance through the medium of means of 65 attachment secured to the rear member at its inner edge.

In the particular embodiment of the invention shown in the drawing, Fig. 1 is a sectional view of a loud speaking receiver embodying the invention;

70 Fig. 2 is a rear view of the device shown in Fig. 1.

A standard 10 carries at its upper end a horizontal member 11, to one end of which is 75 attached an actuating device 12. A conical diaphragm 13 is supported on the horizontal member 11 by means of the frusto-conical member 24 and is operatively associated with the actuating device 12 by means of a 80 rod 25. The frusto-conical member 24 is preferably made of the same material as the diaphragm itself. The outer edge of the member 24 is cemented, or otherwise attached, to the periphery of the diaphragm 85 13. To the inner edge of the member 24 is attached the annulus 20 to which in the present instance the supporting members 27 are secured which in turn are carried by the collar 26.

100 The actuating device 12 may be of any well known type of receiver magnet system, but it is preferable to use one of the type described in Patent No. 1,365,898 of January 18, 1921, to H. C. Egerton, suitably attached 105 to the diaphragm 13, as, for example, in the manner described in my prior application of which the present application is a division.

A diaphragm having a diameter of about 18 inches suitably coupled to the receiver system herein described has been found satisfactory.

5 Acoustic devices of the form and construction substantially as described have been found very effective for the faithful production of sounds covering a wide range of frequencies including those low in the 10 speech and music range, which have been mainly or wholly suppressed by reproducers of the prior art.

The presence of the rear member 24 has been found to increase very materially the 15 effectiveness of the device in producing the lower tones. It will be noted that the diaphragm 13 has different extents of vibration at different frequencies, and as the lowest frequencies are approached more nearly the 20 whole of the diaphragm tends to be effectively involved. The rear of the diaphragm 13 being partially closed off by the rear member 24, there is produced a confining action on the enclosed air at those frequencies 25 at which the diaphragm vibrates effectively throughout most of its area, so that at these low frequencies there is an increase in air movement back and forth through the aperture in the rear member 24. This produces 30 an air mass reactance on the vibrating system in excess of what would be present without the confining action of the member 24, and this excess air mass reactance changes with frequency, being large enough at the 35 low frequencies to offset to a material extent the elasticity reactance of the vibratory system due to its manner of support and permit the system to vibrate more readily and strongly at the low frequencies. At 40 higher frequencies where the diaphragm has a different extent of vibration so that, for example, only a small portion vibrates effectively, this additional effective air mass which is produced by the confining tendency 45 of the rear member 24 at the low frequencies in the manner described above, disappears and permits the diaphragm to vibrate more effectively at the high frequencies than it would if the same mass reactance were present as is present at the low frequencies.

50 A further advantage of the rear member 24 is that it serves to keep the sound issuing from the rear of the diaphragm 13 away from that produced by the front surface of 55 the diaphragm, at least in the region of the reproducer itself, and reduces the loss which may result from an out-of-phase mingling of the sounds from the two sides of the device.

60 Although the invention has been described in connection with a loud speaking receiver, obviously it may be readily adapted to a transmitter, or a phonograph reproducer by substituting means well known in the art 65 for the actuating device described.

What is claimed is:

1. An acoustic device comprising a conical diaphragm, a frustro-conical member secured at its peripheral portion to the peripheral portion of said diaphragm to provide a hollow chamber, and means for supporting the device at the other edge of said frustro-conical member whereby the peripheries of said diaphragm and member are free to vibrate. 70

2. An acoustic device comprising two conical members opposed to each other and secured at their peripheral portions to form a hollow chamber, and means within said chamber for driving one of said members. 75

3. An acoustic device comprising in combination an apertured supporting structure, an outwardly flaring member secured to said supporting structure, a sheet of light thin material secured to said flaring member at its outer edge portion and forming therewith a partial enclosure, and means for vibrating said sheet in accordance with sounds of speech or music frequencies. 80

4. A loud speaker comprising a cone shaped member of paper-like material of the order of 18 inches in diameter, a frustro-cone-shaped member, both members being secured together at their edge portions, said frustro-cone-shaped member having an aperture therein of an area equivalent to the area 90 of a circle equal in diameter to the order of one-half the diameter of said cone-shaped member, means attached to the frustro-cone-shaped member at a distance from its periphery for supporting both members, and means to vibrate the cone-shaped member in accordance with speech or music vibrations. 95

5. A loud speaker comprising two dished sheets secured together at their edge portions to form a hollow enclosure, supporting means attached to one of said sheets remote from its edge and permitting the edge to vibrate, a sound opening in one of said sheets and means inside the enclosure for vibrating one of said sheets in accordance with speech and music vibrations. 100

6. A loud speaker comprising two dished sheets secured together at their edge portions to form a hollow enclosure, a sound opening in one of said sheets, a mounting 115 means for said loud speaker secured to the apertured sheet in the vicinity of the edge of the sound opening therein and permitting the peripheral portions of said sheets to vibrate freely, and driving means supported from said mounting means and provided with a driving connection to a point on the other of said sheets. 120

7. A loud speaker comprising a hollow body presenting oppositely facing dished surfaces uniting with each other at their peripheral portions, a sound opening in one of said surfaces, means remote from the peripheral portion of said loud speaker for mounting the same and permitting the pe- 125 130

- 5 peripheral portion to vibrate freely, an actuating device, supporting means therefor connected to said hollow body in the vicinity of the edge of the sound opening therein, 5 said actuating device having a driving connection to a point in the opposite surface for vibrating said surface in accordance with the sounds to be reproduced.
- 10 8. An acoustic device comprising a front conical member, an inwardly turned rear conical member joined at its base to the front conical member and cut away at its opposite end, a support, and resilient means connecting said rear conical member with 15 said support.
- 15 9. An acoustic device comprising a front conical member, an inwardly turned rear conical member for separating acoustically the rear surface of the front conical member from its front surface, driving means for said front conical member and means for supporting said member so that the edge of said front conical member is free to vibrate when said driving means is active.
- 20 10. An acoustic device comprising a front conical portion, an inwardly turned rear conical portion for separating acoustically the rear surface of the front portion from its front surface and for minimizing the 25 short circuiting of energy around the edge of the front conical portion, a support for said members engaging the rear conical portion, and driving means attached to the front conical portion.
- 30 11. An acoustic device comprising a conical member, driving means therefor attached to the apex thereof, flexible supporting means for the conical member inturned from the base thereof, said flexible supporting 35 means serving to form a partly enclosed chamber for air for the rear surface of the front cone to add air mass reactance and to prevent the short circuiting of energy between the front and rear surfaces of the 40 conical member, and a support coaxial with the axis of the conical member for holding the flexible supporting means and the driving means.
- 45 12. A loud speaker comprising a front cone member of light flexible material, a 50 rear frustro-cone member joined at its outer edge portion to the edge portion of said cone member, means attached to said frustro-cone at a distance from its periphery for supporting both members and means attached to the front cone member for vibrating it in accordance with sounds to be produced, said last means when idle permitting said members to assume a condition free from external tension.
- 55 13. A loud speaker comprising a large direct-acting cone member of light flexible material freely exposed on its exterior side to unconfined air, means on its opposite side for partially confining a body of air comprising a frustro-cone member having its outer edge portion joined to the edge portion of said cone member, means mounted within the enclosure formed by said two members for driving said cone member in 60 accordance with sounds to be produced, and a common support for said driving means and said members.
- 65 14. A loud speaker comprising a cone shaped diaphragm and a frustro-cone shaped member having its outer edge portion secured directly to and continuously along the edge portion of said diaphragm so as to form with said diaphragm a partially enclosed chamber, the inner edge of said frustro-cone member defining an aperture opening to the free air, and means within said chamber for actuating said diaphragm in accordance with sound vibrations.
- 70 15. An acoustic device comprising a large 75 direct acting conical diaphragm, a frustro-conical member secured at its peripheral portion to the peripheral portion of said diaphragm in such a way as to constitute a structure flexible axially and rigid transverse to 80 the axis of the cone, means for supporting the device at the other edge of said frustro-conical member and driving means for said diaphragm positioned within the enclosure formed by said diaphragm and said member.
- 85 In witness whereof, I hereunto subscribe my name this 30th day of November A. D., 90 1925.
